UNITED STATES PATENT OFFICE.

JACOB SCHRAM AND LOUIS SCHRAM, OF CHICAGO, ILLINOIS.

DESIGN FOR A COMBINED EASEL AND FRAME.

SPECIFICATION forming part of Design No. 16,875, dated August 24, 1886.

Application filed June 25, 1886. Serial No. 206,269. Term of patent 7 years.

To all whom it may concern:

Be it known that we, JACOB SCHRAM and LOUIS SCHRAM, citizens of the United States, residing at Chicago, in the county of Cook and State of Illinois, have invented and produced a new and original Design for a Combined Easel and Frame; and we hereby declare the following to be a full, clear, and exact description of the same.

Our design consists in a frame provided with straight extensions and a cross-piece, the whole representing an easel supporting a frame.

The drawing represents our design in elevation.

A is a frame for a picture, mirror, or the like, having straight extensions below in the form of legs *r r*, diverging slightly as they extend, and straight extensions *q q* above in line with the legs *r r*, and converging as they extend, and having the intermediate cross-piece, *o*, the parts *r* and *q* extending, as shown, from the frame, producing with the cross piece *o*

the appearance of an easel supporting a frame. The leg *p* is like the leg commonly used on easels or frames. 25

We claim—

1. The design for a combined easel and frame herein shown and described, the same consisting of the frame A, provided with straight extensions *r* and straight extensions 30 *q*, having the cross-piece *o*, the whole representing an easel supporting a frame.

2. The design for a combined easel and frame herein shown and described, the same consisting of the frame A, provided with 35 straight extensions *r* and straight extensions *q*, having the cross-piece *o*, with the leaf and flower ornamentation, as shown, the whole representing an easel supporting a frame.

JACOB SCHRAM.
LOUIS SCHRAM.
